UNITED STATES PATENT OFFICE.

ARTHUR EDWIN LEIGH SCANES, OF ASHTON-ON-MERSEY, ENGLAND, ASSIGNOR TO
WESTINGHOUSE ELECTRIC & MANUFACTURING COMPANY, A CORPORATION OF
PENNSYLVANIA.

CONDENSER.

1,382,676.

Specification of Letters Patent. Patented June 28, 1921.

Application filed April 10, 1920. Serial No. 372,942.

To all whom it may concern:

Be it known that I, ARTHUR EDWIN LEIGH SCANES, a subject of the King of Great Britain, and a resident of Strathfield, Harboro Road, Ashton-on-Mersey, in the county of Chester, England, have made a new and useful Invention in Condensers, of which the following is a specification.

This invention relates to steam condensers 10 of the surface type in which the steam to be condensed passes over the external surfaces of a plurality of tubes through which the cooling water circulates. The invention has particular reference to the location and arrangement of the tubes within the condenser.

The object of the invention is to reduce the pressure drop of the steam passing through the condenser due to the friction of the steam passing over the condenser tubes.

20 The accompanying drawing is a cross sectional view of a surface condenser with its tubes arranged in accordance with the present invention.

The condenser shell is indicated in dot 25 and dash lines at 1 with a steam inlet 2 at the top and an air outlet 3 with the usual baffle plates near thereto. The usual longitudinal stay is shown at 5. As will be seen from an inspection of the drawing, the arrangement of the tubes 6 is such that the steam entering the inlet 2 will flow downward between the tubes in substantially straight lines in the upper part of the nest of tubes both from the top and at the sides 30 parallel with the direction of the flow at the inlet until it reaches the center portion of the tube nest when the remaining uncondensed steam will follow irregular paths between the remaining tubes in the lower part 35 of the condenser toward the air outlet 3.

40 In condensers of large size it is very desirable to reduce the loss of head through the condenser to a minimum and according to the invention this is accomplished by arranging the tubes so that at the inlet and at 45 the sides of the condenser the parallel lines are substantially parallel with the flow of steam at the inlet, while in the center of the

condenser and near the air outlet, the parallel lines lie in a direction substantially perpendicular thereto. Preferably the surfaces of intersection of the two arrangements of tubing are planes, which facilitates manufacture.

50 While I have shown my invention in but one form, it will be obvious to those skilled in the art that it is not so limited but is susceptible of various other changes and modifications without departing from the spirit thereof and I desire, therefore, that only 55 such limitations shall be placed thereupon as are imposed by the prior art or as are specifically set forth in the appended claims.

What I claim is:

1. A condenser of the surface type having 60 inlet means, outlet means and water tubes, a group of said tubes being arranged in lines parallel to the flow of steam through the inlet and at the sides thereof and other group or groups of tubes arranged in parallel lines 65 perpendicular to the lines of the first group.

2. A condenser provided with a steam inlet and an air outlet, a group of tubes arranged in lines parallel to the flow of steam through 70 said inlet and at the sides thereof, and other tubes within said condenser arranged in lines perpendicular to the lines of the first group 75 and between the first group and the air outlet.

3. A condenser having a steam inlet, an 80 air outlet and a baffle plate contiguous to said air outlet, a group of cooling tubes within the condenser arranged in lines parallel to the direction of flow of steam through the inlet and a second group of 85 cooling tubes arranged in lines perpendicular to the lines of the first group and being overlapped at the ends by tubes of the first group, and other groups of tubes arranged in lines parallel to those of the second group 90 and located between the first two groups and said baffle plate.

In testimony whereof, I have hereunto 95 subscribed my name this twelfth day of March, 1920.

ARTHUR EDWIN LEIGH SCANES.
